DESIGN FOR A HAIRBRUSH BACK AND HANDLE

Freda Diamond, New York, N. Y., assignor to Owens-Illinois Glass Company, Toledo, Ohio,
a corporation of Ohio

Application July 8, 1948, Serial No. 147,433

Term of patent 3½ years

(Cl. D86—10)

To all whom it may concern:

Be it known that I, Freda Diamond, a citizen of the United States, residing at New York, in the State of New York, have invented a new, original, and ornamental Design for a Hairbrush Back and Handle, of which the following is a specification, reference being had to the accompanying drawings, forming a part thereof.

In the drawings:

Fig. 1 is a top plan view of a hairbrush back and handle showing my new design;

Fig. 2 is a side elevational view thereof;

Fig. 3 is an end elevational view of the back; and

Fig. 4 is an end elevational view of the handle portion.

I claim:

The ornamental design for a hairbrush back and handle, substantially as shown.

FREDA DIAMOND.
